UNITED STATES PATENT OFFICE.

ISRAEL MARCUS, OF WINTHROP, MASSACHUSETTS.

RESISTANCE-COIL.

1,268,374.

Specification of Letters Patent. Patented June 4, 1918.

Application filed September 17, 1917. Serial No. 191,831.

To all whom it may concern:

Be it known that I, ISRAEL MARCUS, a citizen of the United States, residing at Winthrop, in the county of Suffolk and State of Massachusetts, have invented certain new and useful Improvements in Resistance-Coils; and I do declare the following to be a full, clear, and exact description of the invention, such as will enable others skilled in the art to which it appertains to make and use the same.

This invention relates to resistance coils adapted to be used as regulators in lighting systems of automobiles in which the current used is produced by a generator attached to the engine shaft whereby when the engine is speeded up the voltage will be increased causing the lights to rise and fall according to the speed of the engine.

20 A further object of my invention is to provide a choke coil to be used in connection with the lighting system as described that will prevent this flickering of the lights.

25 It is my intention to provide a coil which can be adapted to be used on a variety of circuits having different voltages.

30 A further object of the invention is to provide a device of this character in which construction is provided whereby overheating of the coil will be prevented and at the same time all parts thereof will be thoroughly insulated.

35 An additional object of the invention is to provide in a device of this character, a novel form of mounting and insulation for a resistance coil and one which will be easy to manufacture, simple to apply and which will at all times produce its maximum of efficiency.

40 With these general objects in view, and with others subordinate, which will appear in the description, my invention resides in the novel construction, combination and arrangement of parts, to be more fully hereinafter described and claimed and taken in connection with the accompanying drawings forming a part of this specification, and in which:

45 Fig. 1 is a side elevation,

Fig. 2 is a central vertical, longitudinal section,

Fig. 3 is a transverse section taken on the line 3—3 of Fig. 2.

50 As I have illustrated, the preferred em-

bodiment of my invention comprises a substantially hollow, cylindrical shell or casing 1, which is formed preferably of hard rubber but may be composed of any suitable insulating material as desired. The interior 60 of the casing is provided with a central cylindrical bore for about two-thirds of its length as clearly illustrated in Fig. 2 so as to provide for the reception therein of a resistance coil 2, to be described.

65 One end of the casing will be left open while the opposite end 3, will be closed. Centrally disposed, and extending longitudinally through the closed end portion 3, of the casing, is a connector bushing 4, 70 which in this instance comprises a brass tube for receiving a terminal wire of the lighting circuit in which the device is to be utilized. A laterally extending set screw 5 is disposed through the casing and projects into the 75 tube 4, providing means for clamping an end of the wire in the tube and it also serves to retain the tube in position and prevents its accidental disengagement.

80 The resistance coil 2, comprises a hollow or open cylindrical core 6, which is preferably constructed of fiber, having wound thereon a desired number of turns of wire. The completed coil is thoroughly coated with a suitable non-conducting and non-combustible compound so as to render it 85 thoroughly efficient in its operation. The completed coil is placed in the casing through the open end and a plug 7 is detachably engaged in the end of the casing to 90 retain the coil therein.

95 The plug 7, is constructed of hard rubber or of any other suitable insulating material, it is also provided with a longitudinally extending, centrally disposed connector bushing 8 similar in all respects to the hereinbefore described connector bushing 4. Extending through casing and body of the plug 7 is a set screw 9, which projects into the connector bushing 8 serving as means 100 for fastening the plug 7 in position as well as a means for retaining the ends of the wire in the tube and preventing the tube from becoming displaced. The heads of the set screws 5 and 9 are countersunk as illustrated in Fig. 2 so as to provide a uniform compact, cylindrical coil, with no breakable or projecting parts thereon.

105 The terminals of the coil 2 are welded, or in any other manner suitably connected to 110

the brass tubings or bushings 4 and 8 and the bushings are so disposed as to be in alinement and communicating with the open or hollow core of the coil as clearly illustrated in Fig. 2. As the terminals of the circuit wires do not entirely close or fill the tubes 4 and 8, it will be seen that a circulation of the air will be permitted through the center of the coil at all times which will prevent the overheating of the coil thereby assuring a longer life therefor, and a more efficient operation thereof.

When it is desired to use the device in circuits requiring a large resistance it is merely necessary to remove the set screws 5 and 9, take out the plug 7, remove the coil 2 and substitute one of the desired resistance after which the plug is replaced and the device may be then utilized as before, it being merely necessary to insert the terminals of the lighting circuit into the connector bushings 4 and 8 and tighten the set screws.

While I have illustrated in the accompanying drawings, and described in detail, certain specific materials and forms which enter into the construction of my invention I desire it to be understood, that I do not intend to limit myself to this, as these merely form the preferred embodiment of the invention, but any changes may be made in the details of the same which will fall within the scope of the invention as claimed.

I claim:—

35 1. A device as described comprising a cylindrical casing, a resistance coil disposed therein, a plug removably engaged in one end of said casing to retain the coil therein, connector bushings in said casing and plug, connection between the terminals of said coil and bushings, bushing retaining means in the casing, said means serving also to hold the plug in engaged position.

2. In a device as described, a hollow substantially cylindrical insulating casing, a resistance coil having a hollow core disposed therein, a removable plug in one end of the casing, and circuit terminal receiving bushings extending through said casing and plug

in communication with the core of said coil 50 to permit circulation of air therethrough and prevent overheating of the coil, and connections between said bushings and the terminals of said coil.

3. A device as described, comprising a hollow substantially cylindrical insulating casing having an open end, the other end of said casing being provided with an aperture, a resistance coil disposed in the interior of said casing, a plug detachably mounted in the open end of the casing, connector bushings in said closed end of the casing and through said plug in connection with the terminals of said coil, wire retaining members in the casing and extending into 65 said bushings to prevent displacement thereof, one of said members extending through said casing into said plug connector bushing to engage and retain said plug.

4. In a device as described, a hollow substantially cylindrical casing having an open end, the other end of said casing being provided with an aperture, a resistance coil having an open cylindrical fiber core disposed in said casing through said open end, 75 an insulating plug to be removably engaged in said open end to retain the coil in said casing, said plug being provided with an opening, metal tubes extending longitudinally in said openings in said casing and 80 plug respectively and communicating with the core of said coil thereby permitting air to circulate therethrough, connection between said tubes and terminals of said coils, set screws extending laterally through said casing and into said tubes for clamping circuit terminals therein and holding said tubes in position and one of said screws extending through the casing plug and adjacent tube whereby to hold the said plug in engagement.

In testimony whereof I have hereunto set my hand in the presence of two subscribing witnesses.

ISRAEL MARCUS.
